UNITED STATES PATENT OFFICE.

HANS EDUARD THEISEN, OF MUNICH, GERMANY.

APPARATUS FOR CLEANSING, COOLING, AND MIXING GASES.

1,088,186.

Specification of Letters Patent. Patented Feb. 24, 1914.

Application filed March 18, 1913. Serial No. 755,076.

To all whom it may concern:

Be it known that I, HANS EDUARD THEISEN, a citizen of the United States of America, residing at Munich, in Germany, have invented certain new and useful Improvements in Apparatus for Cleansing, Cooling, and Mixing Gases, of which the following is a specification.

My invention relates to apparatus of the type wherein gases are cleansed, cooled or mixed in the course of their passage through a casing containing fixed rings of perforated sheet metal, wire fabric or equivalent material, between which rotate similar rings, in the manner of the beaters of a disintegrator, the two sets of rings being usually carried by disks, one of which is fixed to a shaft.

My invention consists in certain improvements in apparatus of this type, all of which will now be described with reference to the accompanying drawings, in which—

Figure 1 is an elevation, partly in section, showing one embodiment of the invention. Figs. 2 and 3 are sectional views, partly broken away, showing two other embodiments, and Fig. 4 is a sectional view showing a modification of part of the construction shown in Fig. 1.

In the construction shown in Fig. 1, σ and ρ designate two casings or chambers formed at opposite sides of a chamber ι , with which they communicate, the chamber ι containing a fan k whereby gas can be forced or drawn through the chambers σ and ρ . The bent or inclined vanes of the fan rotate close to the conical walls g of the chamber ι . In each of the chambers σ and ρ is a disk b , fitted into a seat in the wall, the said seat surrounding the opening whereby the chamber communicates with the chamber ι . The disk b has a central opening for passage of the gas, but projects to some extent over the opening in the wall of the chamber, as shown at d . The part d accordingly determines the size of the opening available for the passage of the gas, this opening being proportioned so as to secure a uniform flow of gas from one chamber to the other. Fixed to the disk b are three concentric rings m , which project into the chamber and lie between rings n fixed to a disk on the shaft of the fan. Around its opening leading to the chamber ι each of the chambers σ and ρ has in its wall a channel a which is covered by the

disk b and to which liquid for washing or cooling the gas is admitted by means of a pipe e . Short tubes c fixed to the disk b project from this channel into the chamber and have holes directed toward the innermost concentric ring, so that jets of liquid are projected toward that ring. The disk b can be pressed away from its seat by means of screws f , the heads of which lie outside the chamber containing it. It will be understood that a separate cover may be used for the channel a , but I prefer the more simple construction described, wherein the disk b supporting the fixed rings also forms the cover for the channel.

The apparatus shown in Fig. 2 comprises a single chamber g^1 , in which the vanes of the fan, designated k^1 , are placed around the rings m^1 , n^1 , the rings n^1 being fixed to the fan and the rings m^1 being fixed to disks b^1 on the walls of the chamber. There are two sets of vanes, and two sets of rings m^1 , n^1 . In the walls of the chamber are annular distributing channels a^1 , to which liquid is fed by pipes e^1 , and from which the liquid is discharged through tubes having holes directed toward the rings, so that jets of liquid or spray issue as indicated in the drawing. It will be understood that the fan may be constructed and driven so that the gas flows either in the same direction as the jets of liquid, or in the opposite direction.

The apparatus shown in Fig. 3 comprises a fan k^{11} with a single set of vanes arranged around perforated rings m^{11} , n^{11} , the rings m^{11} being fixed to a disk b^{11} from which project spray tubes c^{11} communicating with a distributing channel a^{11} in one wall of the chamber. Liquid is supplied to this channel by a pipe e^{11} .

Fig. 4 shows a modification applied to a construction similar to that shown in Fig. 1, the fan k^{11} being arranged in a chamber ι^{11} , which communicates with the chamber (not shown in Fig. 4) containing the fixed and rotating rings. There is a distributing channel a^{11} , to which liquid is supplied through a pipe e^{11} , and from which liquid is discharged through spray tubes c^{11} , as in the constructions previously described, but the wall of the channel nearest the chamber ι^{11} has ducts h through which streams of liquid are directed on to the conical walls g^{11} of the chamber ι^{11} along which the vanes of the fan sweep. The same wall has

- ducts *i* through which liquid is projected into the interior of the fan chamber, this liquid being flung against the walls *g* by the vanes.
5. What I claim as my invention and desire to secure by Letters Patent of the United States is:—
1. In apparatus for the purpose set forth, the combination of a casing having a covered annular channel in one of its walls, means for supplying liquid to said channel, a fixed perforated ring in said casing, a rotatable perforated ring concentric with said fixed ring in said casing, and sprayer tubes communicating with said channel, arranged within the circumference of the inner ring.
  2. In apparatus for the purpose set forth, the combination of a casing having an annular channel in one of its walls, means for supplying liquid to said channel, a disk in said casing covering said channel, a perforated ring fixed to said disk, a rotatable perforated ring concentric with said fixed ring in said casing, and sprayer tubes communicating with said channel, arranged within the circumference of the inner ring.
  3. In apparatus for the purpose set forth, the combination of a casing having an opening in one of its walls and a covered annular channel extending around said opening, means for supplying liquid to said channel, a chamber joined to the wall having said opening, a fan in said chamber, a fixed perforated ring in said casing, a rotatable perforated ring concentric with said fixed ring in said casing, and sprayer tubes communicating with said channel, arranged within the circumference of the inner ring.
  4. In apparatus for the purpose set forth, the combination of a casing having an opening in one of its walls and an internal annular channel extending around said opening, means for supplying liquid to said channel, a chamber joined to the wall having said opening, a fan in said chamber, a disk having a central aperture, covering said channel and partly covering said opening, a perforated ring fixed to said disk, a rotatable perforated ring concentric with said fixed ring in said casing, and sprayer tubes communicating with said channel, arranged within the circumference of the inner ring.
  5. In apparatus for the purpose set forth, the combination of a casing having an annular channel in one of its walls, means for supplying liquid to said channel, a disk in said casing covering said channel, screws passing through said wall, whereby said disk can be pressed away from said channel, a perforated ring fixed to said disk, a rotatable perforated ring concentric with said fixed ring in said casing, and sprayer tubes communicating with said channel, arranged within the circumference of the inner ring.
  6. In apparatus for the purpose set forth, the combination of a casing having an opening in one of its walls and a covered annular channel extending around said opening, means for supplying liquid to said channel, a chamber joined to the wall having said opening, a fan in said chamber, a fixed perforated ring in said casing, a rotatable perforated ring concentric with said fixed ring in said casing, and sprayer tubes communicating with said channel, arranged within the circumference of the inner ring.
  7. In apparatus for the purpose set forth, the combination of a casing having an opening in one of its walls and a covered annular channel extending around said opening, means for supplying liquid to said channel, a chamber joined to the wall having said opening, a fan in said chamber, a fixed perforated ring in said casing, a rotatable perforated ring concentric with said fixed ring in said casing, and sprayer tubes communicating with said channel, arranged within the circumference of the inner ring, said chamber having coned walls joined to said casing, and one wall of said channel having holes whereby jets of liquid can issue from said channel and impinge on said coned walls.
  8. In apparatus for the purpose set forth, the combination of a casing having an opening in one of its walls and a covered annular channel extending around said opening, means for supplying liquid to said channel, a chamber joined to the wall having said opening, a fan in said chamber, a fixed perforated ring in said casing, a rotatable perforated ring concentric with said fixed ring in said casing, sprayer tubes communicating with said channel, arranged within the circumference of the inner ring, and a longitudinal dividing wall in said channel, one wall of said channel having holes whereby jets of liquid from one side of said dividing wall can pass into said chamber.
- In witness whereof I have signed this specification in the presence of two witnesses.
- HANS EDUARD THIELSEN.
